ECONOMIZER

Albert C. Schleh, St. Paul, Minn.

Application May 29, 1933. Serial No. 673,432

10 Claims. (Cl. 257—167)

My invention relates to economizers and has for its object to provide an economizer by means of which the waste heat in the flue gas of heating plants may be utilized to heat air for circulation in rooms of buildings and for the purpose of evaporating water to humidify such air.

An object of the invention resides in providing an economizer of such type which will be highly efficient in operation and which will not appreciably impair the flow of the flue gas or the flow of the heated air.

Another object of the invention resides in constructing the economizer with a case having spaced partitions therein providing chambers at the ends of the case and in further providing cylindrical ducts between said partitions for bringing said chambers into communication with one another, said ducts being arranged to form reentrant angles between one another.

20 An object of the invention resides in providing a deflector adapted to be inserted in the reentrant angle between two of said ducts for causing the gas passing about the ducts to follow closely along the surface thereof.

25 Another object of the invention resides in mounting the deflector for movement in and out of said reentrant angle to adjust the course of the flue gas in passing about the ducts.

A feature of the invention resides in constructing the deflector in the form of a plate and in pivotally mounting said deflector to swing into and out of the reentrant angle.

Another object of the invention resides in constructing the case with an opening opposite the reentrant angle between the ducts and in providing a closure for closing said opening.

A still further object of the invention resides in mounting the deflector on said closure.

A feature of the invention resides in constructing the deflector with a slot and in providing an adjusting screw having a disk on the end thereof for engagement with said slot by means of which the deflector may be swung upon its axis.

Another object of the invention resides in the specific construction of the deflector.

A still further object of the invention resides in the specific construction of the closure.

An object of the invention resides in spacing two of the ducts with respect to one another and 50 in providing a baffle between them for connecting the same and for directing the flue gas about the other ducts.

A still further object of the invention resides in constructing said baffle with a shelf and with 55 side walls extending up to the case and to the

upper partition to form in conjunction therewith a pocket in which heated flue gas may be directed.

An object of the invention resides in constructing the upper partition of the economizer to provide a pan in which water may be placed and in arranging said pan to maintain water over the pocket formed in said passageway.

A feature of the invention resides in the specific construction by means of which the ducts are attached to the partitions of the economizer. Other objects of the invention reside in the novel combination and arrangement of parts and in the details of construction hereinafter illustrated and/or described.

In the drawings:

Fig. 1 is a side elevational view of an economizer illustrating an embodiment of my invention and showing a portion of the case cut away to illustrate the interior construction of the economizer.

Fig. 2 is a plan sectional view taken on line 2—2 of Fig. 1.

Fig. 3 is an elevational sectional view taken on line 3—3 of Fig. 2.

Fig. 4 is a sectional elevational view taken on line 4—4 of Fig. 2.

Fig. 5 is a fragmentary plan sectional view taken on line 5—5 of Fig. 1.

Fig. 6 is a plan sectional view taken through the adjusting mechanism of one of the deflectors and drawn to a larger scale.

Fig. 7 is a sectional detail view showing the method of attaching the duct to the partition of the case.

Fig. 8 is a view similar to Fig. 7 showing the construction of one of the closures for the case.

In the use of economizers having a plurality of circular ducts it has heretofore been impossible to cause the flue gas to circulate about said ducts and to uniformly heat the entire surfaces thereof. In such construction considerable difficulty is encountered in cleaning the economizer and in the attachment of the ducts to the inner structures of the economizer to form a gas tight joint. The present invention provides a device in which these various problems are solved in a simple and expeditious manner and by means of which the desired results and other advantages are attained.

My invention consists of a case indicated in its entirety at A which case is preferably constructed of sheet metal and comprises end walls 10 and 11 and front and rear walls 12 and 13. At the top of the case is provided a hood 14 110

which is connected to the front, rear and end walls of the case and which is constructed with a top 15, flared ends 16 and sides 17. The various parts of the hood 14 are constructed of sheet metal and are secured together through standing seams 18 or the same may be attached to one another in any other desirable manner. At the lower end of the case A is provided a similar hood 19 which is constructed in much the same manner, being provided with a bottom 20 inclined ends 21 and sides 22. These parts may likewise be secured together by suitable seams or the same may be welded or attached to each other in any other manner.

15 Within the interior of the case A are provided two partitions 23 and 24 which are arranged in horizontal position and which extend across the various walls of the said case. The partition 23 is formed with an upstanding flange 25 extending perimetrically about the same, which flange is turned back upon itself as indicated at 26 to receive the upper ends of the various walls 10, 11, 12 and 13 of the case proper. The partition 24 is constructed with a similar flange 27 extending outwardly therefrom, which flange is bent back upon itself as indicated at 28 to receive the various lower ends of the walls of the case A. By means of this construction the said partitions are held in position upon the ends of the case. The hood 17 is provided with inwardly turned flanges 29 which rest upon the upper ends of the parts 25 and 26 of partition 23 and with lips 30 turned inwardly therefrom and following along the flanges 25. In like manner the hood 19 is provided with an inwardly turned flange 31 and with a lip 32 for engagement with the parts 27-28 of the partition 24. By means of this construction the two hoods are supported relative to the case proper and in such a manner as to form a sufficiently tight joint so that escape of gas from the case is entirely prevented. It will readily be comprehended, however, that the case may be constructed in any other suitable manner such as is well known in the art and the various parts secured together through the various different forms of seams or welded or riveted as found desirable.

16 The economizer rests upon a supporting structure indicated in its entirety by the reference numeral 33. This supporting structure includes four legs 34 which have attached to them at their upper ends transversely disposed angle members 35 and 36 and longitudinal frame members 37 and 38 which hold the said legs in proper position. These parts may be riveted, bolted or welded together or attached to one another in any suitable manner. The lower hood 19 of the economizer rests directly upon the supporting structure 33, the various seams connecting the bottom 20 thereof to the walls of said hood straddling the parts of the supporting structure and holding the entire economizer in position thereon.

17 Within the interior of the case A are provided four cylindrical ducts 39, 40, 41 and 42 which are constructed of sheet metal and which extend between the two partitions 23 and 24. These partitions are provided with suitable openings communicating with said ducts and are formed with lips 43 turned upwardly therefrom. These lips when the ducts are in proper position, form a continuation of said ducts. The ends of the ducts are provided with outwardly extending flanges 44 which abut against the under surface 75 of the partition 23 and the upper surface of the

partition 24. These flanges hold the partitions spaced and form part of the joint between the said partitions and ducts. Within the various ducts at both ends thereof are provided sleeves 45 which fit snugly within the interiors of said ducts and which are welded thereto. These sleeves extend through the circular lips 43 and the extreme ends 46 of said sleeves are turned back over the lips 43 to clamp the said ducts in position against the two partitions 23 and 24. By means of this construction the ducts are securely attached to the said partitions and the partitions are held attached to the wall structure of the case proper.

18 By the arrangement of parts thus shown, the upper partition 23 between the various ducts and the walls of the case, forms a pan which is used for the purpose of providing humidification as will be presently described in detail. By means of the ducts and casing and the partitions extending across the casing, two chambers 47 and 48 are provided at the upper and lower ends of the case A which chambers are in communication through the ducts. About the exteriors of said ducts and between the two partitions 23 and 24 is formed a passageway 49. The flue gas from which the heat is to be procured is passed through the passageway 49 while the air to which the heat is to be transferred passes through the various ducts 39, 40, 41 and 42. For the purpose of leading the air to be heated into the economizer a conduit 50 is provided which is attached to the bottom 20 of hood 19, and which is in communication with the chamber 48. A similar conduit 51 is attached to the top 15 of hood 17 and is in communication with the chamber 47. Conduit 50 is connected to the cold air return of the room whose air is to be heated while conduit 51 is connected to a warm air pipe adapted to deliver the heated air to the desired locality. As the various ducts are heated through the flue gas the air passes from the conduit 50 into chamber 48 and from said chamber through the ducts 39, 40, 41 and 42 and into chamber 47. From the chamber 47 the air is delivered through the conduit 51 to the desired locality.

19 For conducting the flue gas into and out of the passageway 49, a pipe 52 is employed which is connected to the front wall 12 of case 10, near the upper end of the same. A similar pipe 53 is connected to the rear wall 13 of said case. Both of these pipes communicate with the passageway 49. To prevent the flue gas from short circuiting across the economizer, a baffle 54 is employed which is disposed between the two conduits 40 and 41. The baffle 54 is of considerable width and the two conduits 40 and 41 are spaced to receive the same. This baffle may be attached to the said conduits through complementary angles 55 which are secured to said conduit and to said baffle. The baffle 54 is constructed of sheet metal and extends up to a short distance of the underside of the partition 23. At such locality the same is bent to form a shelf 56 which extends rearwardly toward the rear wall 13 of case A and at a locality immediately above the pipe 53. At the sides of this shelf are provided walls 57 and 58 which extend upwardly from said shelf and meet the rear wall 13 and the partition 23. These walls are tangent to the walls of the ducts 40 and 41 and form a pocket 59 at the central portion of the partition 23 which pocket receives the flue gas when the same first enters the economizer. In this manner the part of the partition 23 immediately above pocket 59 is main- 150

tained at the highest temperature in the economizer. The ducts 39—40 and the ducts 41—42 may be arranged closer together than the ducts 40—41. In such case the space between said 5 ducts may be closed through pairs of angle members 60 and 61 which are attached to the said ducts and which abut against one another. By means of this construction the passageway 49 extends continuously about the various ducts. 10 This passageway divides at the baffle 54, one branch extending to the right and about ducts 41 and 42, the other branch extending to the left and about ducts 40—39. Both of these branches 15 of the passageway meet on the opposite side of the baffle 54 where they directly communicate with the pipe 53 and bring the flue gas to the smoke pipe leading to the chimney.

For the purpose of cleaning the interior of the case A, the front and rear walls 12 and 13 therefore 20 are constructed with openings indicated at 62 in Figs. 1 and 8, which openings are disposed opposite the pairs of ducts 39 and 40 and 41 and 42. At the edges of the openings 62 the front and rear walls 12 and 13 of case A are provided 25 outwardly extending flanges 66. The openings 62 are adapted to be closed by closures 64, each of which consists of an outer wall 65 which overlies said openings and which seat against the flanges 66 formed on the front and rear walls 30 of the case. The walls 65 are formed with beveled edges 67 which extend up to the outer surfaces of the walls 12 and 13. Upon the inner surface of the outer wall 65 of said closure are provided 35 liners 68 which are constructed with flanges 69 abutting against the same. These flanges fit within the flanges 66 and assist in forming a gas tight joint between the said closures and the case proper. The liners may be attached to the 40 closures by bolts, rivets or otherwise, which construction has not been shown. Within the interior of the case A is provided a rectangular frame 70, there being one such frame for each 45 of the openings 62. These frames are riveted to the front and rear walls and project inwardly into said openings the same serving as abutments for engagement with the liner 68. Suitable screws 71 pass through both the outer wall 65 and the liner 68 which screws are threaded 50 into the frame 70 and serve to hold the closures rigidly attached to the case in a manner to provide a gas tight joint therebetween.

It will be noted in Fig. 2 that the ducts 39 and 40 and the ducts 41 and 42 are so arranged that 55 reentrant angles 72 and 73, 77 and 76 are formed between the same. Considerable difficulty has heretofore been encountered in causing the flue gas to enter these angles of the gas passageway, resulting in a higher stack temperature than desired. To cause the flue gas to follow 60 about the surfaces of the ducts, deflectors 74 and 75 are employed which are disposed in certain of these angles. For the purpose of simplicity, deflectors have been shown only in angles 72 and 73, though similar deflectors 65 may also be used in angles 76 and 77 which are formed on the opposite sides of the ducts. The construction of the various deflectors being identical, only the deflector 74 will be described, which is shown in detail in Fig. 6. This deflector consists of a plate 78 which is constructed 70 of sheet metal and extends vertically within the passageway 49. Near the middle of said plate is provided an offset 79 and at the end of said plate is formed a lip 80 which extends outwardly therefrom and which serves to stiffen and reinforce

the same. At the edge of the plate 78 is provided a hinge 81 which is secured to the liner 68 of closure 64 and by means of which the plate may swing from the position shown in full lines in Fig. 6 to the position shown in dotted lines in said figure. The plate 78 may be swung from one position to the other through an adjusting screw 181 which is mounted for rotation with respect to the closure 64. This screw is threaded into a plate 82 which is welded or riveted to the liner 68 of closure 64. A sleeve 83 encircles this screw and is disposed between said liner and the outer wall 65 of said closure. Upon the exterior of the outer wall 65 is provided a nut 84 which is also threaded upon the screw 181 and by means of which the said screw may be locked in position. A finger piece 85 is attached to the end of the adjusting screw 181 by means of which the same may be manipulated. Upon the end of the screw 181 and within the passageway 49 is disposed a disk 86 which is firmly secured to said screw. This disk is adapted to enter the slot 87 in the offset portion 79 of plate 78. When the screw 181 is moved inwardly, said disk shifts the deflector plate 78 toward its full line position and when the screw 181 is moved outwardly, the deflector plate 78 is shifted to the position shown in dotted lines. By means of this construction the deflector plate can be arranged to cause the flue gas to travel about the surfaces of the various ducts of the economizer or the same can be permitted to travel directly along the front and rear walls of the case without entering completely into the reentrant angles formed between the ducts. In an installation where the draft is poor, the deflector plates 78 are adjusted to a position more nearly approaching that shown in dotted lines in Fig. 6. Where the draft is sufficient, the plates may be swung as shown in full lines, causing the air to be more completely heated and the greater percentage of the heat secured from the flue gas as the same passes through the economizer. 105

For the purpose of distributing the air entering the economizer through inlet conduit 50, two distributor plates 88 and 89 are employed which extend across the two walls 22 of hood 19 and extend up to the partition 24 at localities intermediate the two sets of ducts 39—40 and 41—42. These partitions further extend up to the conduit 110 50. By means of these plates the air is divided, part going to each of the several ducts and heated in its passage upwardly through said duct. 115

My economizer in addition to absorbing heat from the flue gases of the heating plant operates 120 to humidify the air passing through the device. For this purpose the partition 23 is constructed to form a pan 93 which is accomplished by turning up the edges of the same at the marginal portions thereof to form the flanges 25 and about the various openings through which the ducts 39, 40, 41 and 42 extend to form the flanges 43. This pan is constructed with a depression 90 at the center thereof immediately above the pocket 59. The water is brought into the pan formed in partition 125 23 through a water controlling device 91 connected to a suitable water pipe 92. The device 91 includes an ordinary float and a valve operated thereby by means of which the level of the water within the pan 93 may be maintained at such 130 elevation as to not overflow the upper edges of the various flanges of the same. Due to the pocket 59 the depressed portion 90 of the pan is maintained at a particularly high temperature 135 so that evaporation at this locality is always cer- 140

145

150

tain to occur. By means of the construction described, the heat from the flue gas is caused to humidify the air entering chamber 47 prior to its removal from the economizer through the conduit 51. The water controlling device 91 maintains the water at the proper level in pan 93 so that as the water is evaporated additional water is added to replace the same.

The operation of my invention is as follows: 10 The flue gas enters the passageway 49 through the pipe 52 and strikes the baffle 54. The gas then divides, part passing to the right and part passing to the left, the portions of the gas thus traveling passing about the various ducts 39, 40, 41 and 42. 15 On the opposite side of the case A the parts of the flue gas again unite and pass outwardly through the pipe 53. The air in entering the economizer through the conduit 50 is divided through the plates 88-89 and part of the same 20 passes through each of the various ducts 39, 40, 41 and 42. During such travel of the air the same is heated. The heat from the flue gas also heats the partition 23 which causes the water disposed in pan 93 to evaporate. The air on entering chamber 47 is mixed with the steam and water vapor disposed within said chamber and liberated from pan 93 and leaves the economizer through conduit 51 in a humidified condition.

My invention is highly advantageous in that 25 an extremely simple and practical construction is provided whereby the heat ordinarily wasted in flue gases may be utilized. The device is adapted to be used for heating the air of rooms and operates to efficiently transfer a large part of the 30 wasted heat to such air. By means of the humidifying apparatus shown, the air prior to its leaving the economizer is provided with sufficient humidity. Due to the construction of the pocket for hot flue gases below the humidifying pan, 35 sufficient heat is always provided at such locality to cause evaporation regardless of whether or not sufficient heat is available to cause evaporation over the entire surface of the pan. By means of the deflector plates the flue gas can be caused 40 to travel in close proximity to the entire surface of the various conduits thereby procuring greater efficiency. By means of the adjusting mechanism the deflector plates can be adjusted so as to cause 45 any rate of flow of flue gases desired, depending upon the chimney conditions and the type and construction of the heating plant.

Changes in the specific form of my invention, as herein disclosed, may be made within the scope of what is claimed without departing from the 50 spirit of my invention.

Having described my invention, what I claim as new and desire to protect by Letters Patent is:

1. In an economizer, a case, spaced partitions in said case forming chambers at the ends of the 55 case, a plurality of juxtaposed cylindrical ducts extending between said partitions and bringing said chambers into communication, said ducts being arranged to form a reentrant angle therebetween, said case forming in conjunction with said ducts a passageway extending about said ducts, and a deflector carried by said case and extending into said reentrant angle, said deflector having a surface extending substantially in the same direction as the direction of extent of the 60 surface of one of said ducts at said reentrant angle.

2. In an economizer, a case, spaced partitions in said case forming chambers at the ends of the case, a plurality of juxtaposed cylindrical ducts 65 extending between said partitions and bringing

said chambers into communication, said ducts being arranged to form a reentrant angle therebetween, said case forming in conjunction with said ducts a passageway extending about said ducts, a deflector plate pivoted to said case and being adapted to swing into the space defined by said reentrant angle to a position substantially parallel with the portion of one of the ducts at said angle and to swing into a position substantially parallel with the general direction of extent of said passageway at such locality. 80

3. In an economizer, a case, spaced partitions in said case forming chambers at the ends of the case, a plurality of juxtaposed cylindrical ducts extending between said partitions and bringing said chambers into communication, said ducts being arranged to form a reentrant angle therebetween, said case forming in conjunction with said ducts a passageway extending about said ducts, a deflector movably mounted within said 85 case and means for guiding said deflector for movement into and out of said reentrant angle. 90

4. In an economizer, a case, spaced partitions in said case forming chambers at the ends of the case, a plurality of juxtaposed cylindrical ducts 100 extending between said partitions and bringing said chambers into communication, said ducts being arranged to form a reentrant angle therebetween, said case forming in conjunction with said ducts a passageway extending about 105 said ducts, said case having a clean-out opening disposed therein in proximity to said reentrant angle, a closure for said opening and a deflector carried by said closure and extending into said reentrant angle. 110

5. In an economizer, a case, spaced partitions in said case forming chambers at the ends of the case, a plurality of juxtaposed cylindrical ducts extending between said partitions and bringing said chambers into communication, said ducts 115 being arranged to form a reentrant angle therebetween, said case forming in conjunction with said ducts a passageway extending about said ducts, a deflector plate pivoted to said case upon the interior thereof, said deflector plate having 120 a slot therein, an adjusting screw threaded in said case and extending therethrough, said adjusting screw having a disk thereon for engagement with said slot by means of which the plate may be swung into or out of said reentrant angle 125 upon rotation of said screw.

6. In an economizer, a case, spaced partitions in said case forming chambers at the ends of the case, a plurality of juxtaposed cylindrical ducts extending between said partitions and bringing said chambers into communication, said ducts being arranged to form a reentrant angle therebetween, said case forming in conjunction with said ducts a passageway extending about said ducts, a deflector plate pivoted to said case upon 130 the interior thereof, said deflector plate having an offset portion formed with a slot therein, an adjusting screw threaded in said case and extending therethrough and a disk on said adjusting screw for engagement with said slot. 135

7. In an economizer, a case, spaced partitions in said case forming chambers at the ends of the case, a cylindrical duct extending between said partitions and bringing said chambers into communication, said duct having an outwardly turned flange at one end for engagement with one of said partitions, a sleeve disposed within said end of the duct and secured thereto, a flange formed on said partition and following along said sleeve, said sleeve having an edge turned over 140 145

150

- the outer end of said partition flange to hold the duct attached to said partition.
8. In an economizer, a case, spaced partitions in said case forming chambers at the ends of the case, a plurality of juxtaposed cylindrical ducts extending between said partitions and bringing said chambers into communication, said ducts being arranged to form a reentrant angle therebetween, said case forming in conjunction with said ducts a passageway extending about said ducts, said case having an opening therein opposite said reentrant angle, a flange extending outwardly from said case about said opening, a closure for said opening, said closure comprising an outer wall adapted to seat upon the edge of said flange and formed with beveled edges extending up to said case, a liner upon the inner surface of said closure, said liner being spaced from said closure and being formed with flanges engaging said closure, said flanges being received within the flanges of said case.
9. In an economizer, a case, spaced partitions in said case forming chambers at the ends of the case, a plurality of juxtaposed ducts extending between said partitions and bringing said chambers into communication, said ducts being arranged in a row, two of the intermediate of the ducts being spaced from one another, a baffle disposed between said intermediate ducts, said case being constructed to form in conjunction with said ducts and baffle a flue gas passageway extending about said ducts, a shelf extending outwardly from said baffle and spaced from one of said partitions, side walls disposed between said case, a baffle, partition and shelf to form a pocket therein, said partition being constructed to provide a receptacle for water adapted to be heated through gas entering said pocket.
10. In an economizer, a case, spaced partitions in said case forming chambers at the end of the case, a plurality of juxtaposed cylindrical ducts extending between said partitions and bringing said chambers into communication, said ducts being arranged to form a space therebetween, said case forming in conjunction with said ducts a passageway extending about said ducts, and an elongated deflector of a width less than the diameter of the ducts carried by a wall of said case parallel with said ducts, said deflector extending in the same direction as said ducts and projecting into said space, said deflector being free from the case and ducts at its inner end.
